N. Y., assignors to Hillfox Manufacturing Cor-
poration, Rochester, N. Y.

Application January 2, 1935, Serial No. 129

7 Claims. (Cl. 30—210)

This invention relates to hair clippers and has for its object to provide a novel form of clippers which is especially adapted for use in closely cutting superfluous hair of the body.

5 Another object of this invention is to provide the clippers with a novel form of cutting blade with which the hair can be efficiently cut on flat as well as convexly and concavely curved surfaces of the body.

10 A further object of this invention is to provide the clippers with a novel operating mechanism.

All these and other objects of this invention will become more readily apparent from the detailed description thereof which follows, reference being had to the accompanying drawing in which

Figure 1 is a side elevation of the novel clippers.

Figure 2 is a longitudinal sectional view of the clippers.

20 Figure 3 is an enlarged vertical sectional view of the head of the clippers, the section being taken on the line 3x—3x of Figure 2.

Figure 4 is a horizontal sectional view of the head of the clippers, the section being taken on the line 4x—4x of Figure 3.

Figure 5 is a horizontal sectional view of the clippers taken on the line 5x—5x of Figure 3.

In the several figures of the drawing like reference numerals indicate like parts.

30 The novel form of clippers for cutting the superfluous hair of the body forming the subject matter of our present invention makes these clippers especially adapted for use in closely clipping the hair in concaved portions of the body such as, for example, in the arm pits although the clippers will clip the hair equally well on the more or less convex portions of the body.

As illustrated in the several figures of the drawing the clippers has an elongated preferably cylindrical hollow handle 1 to which is threaded the cap 2. This cap is enlarged at its junction with the handle 1 so as to provide an annular ridge 3 which projects beyond the outer wall of the handle for a purpose that will hereinafter be described. From the outwardly projecting ridge 3 the cap tapers toward the top to provide a reduced outer end 4 thereon to have the cutter head form a continuation thereof.

50 The cutter head comprises the stationary circular cutter disc 5 located on the outside of the clipper head and the oscillating circular cutter disc 6 located on the under side of the stationary disc. Suitable teeth 7 and 8 are provided in the periphery of these respective cutter discs which

cooperate to closely clip the hair as it enters the openings between the teeth.

The outer stationary cutter disc is held supported on the outer end of the supporting rod 9 and is clamped to the shoulder 10 thereof by means of the nut 11 and lock washer 12. The supporting rod in turn is fixedly anchored in the base 13 which is clamped in place in the end of the handle 1 by means of the cap 2. Supported by a suitable bearing plate 14 on the base 13 and 10 surrounding the supporting rod 9 is the driving sleeve 15 which is oscillated to operate the cutter disc 6. For this purpose the outer end of the driving sleeve carries the driving disc 16 which is provided with a series of driving pins 17 which engage into suitable holes in the cutter disc 6 to hold this disc centered thereon and fixed thereto. A spider shaped spring 18 is interposed between the driving disc 16 and the under side of the cutter disc 6 and operates to hold the cutter disc 6 yieldingly against the under side of the cutter disc 5. Suitable short lugs 19 project from the driving disc and hold the spider shaped spring in a predetermined fixed position on the driving disc 16 between it and the cutter disc 6. 25

The driving sleeve is provided near its inner end with the driving pin 20 which projects radially therefrom and carries the connecting bearing 21. This bearing is slidably mounted in the outer end of the oscillating arm 22 so that on 30 the oscillation thereof the bearing provides a floating connection between the arm 22 and the pin 21 and oscillates the driving sleeve in a horizontal plane on the oscillation of the arm in a vertical plane. The arm 22 forms part of the 35 yoke shaped operating member 23 which is mounted to oscillate on the pivot shaft 24. Movement is transmitted to the operating member thru the rocker arm 25 which is fulcrumed on the pin 26 and engages the under side of the operating member with its outer end. At a point intermediate its fulcrum and its point of engagement with the operating member, the rocker arm is provided with a pocket 27 into which engages the end of the operating rod 28. This rod is non-magnetic and is mounted to slide and projects thru the fixed armature 29 into engagement with the end of the movable core 30 of the solenoid 31. An expansion spring 32 acting against the lower end of the movable core yieldingly supports 50 the movable solenoid against the pressure of spring arm 32A which is mounted in the base 13 and exerts a downward pressure against the operating yoke 23 and thru the rocker arm 25 against the operating rod 28 so that the movable

core is held suspended in a floating position within the solenoid 31.

The solenoid is supported on the base 33 which in turn rests on the shoulder 34 within the handle

- 5 1. In this way the cap 2, when threaded onto the handle 1, holds the base 13 down onto the solenoid 31 and the solenoid against the base 33 which in turn holds the base 33 against the shoulder 34 so that all of these members are firmly held together and fixedly mounted in the handle by the attachment of the cap 2 thereto. A cork or other resilient washer 35 is interposed between the base 13 and the solenoid to take up any slight variation in the length of these members and prevent 15 too great a pressure from being exerted on any one of them.

Suitable terminals 36 and 37 are carried by the base 33 and are connected to the leads of the solenoid to provide for the electrical connection 20 by means of a suitable extension cord 38 which enters the bottom of the handle 1 thru the opening 39.

From the foregoing it will be apparent that the reciprocating motion of the floating core 30, caused by an alternating current passing thru the solenoid, reciprocates the operating rod 28 and oscillates the operating yoke 23 and its arm 22 by means of the rocker arm 25. The oscillating motion of the arm 22 in turn is transmitted 30 to the driving sleeve 14 by means of the connecting pin 20 and its connecting head 21, and the driving disc 16, carried by the driving sleeve, causes the cutter disc 6 to oscillate on the under side of the stationary cutter disc 5 for the cutting 35 operation.

As will be seen from an inspection of Figure 1 the annular ridge 3 of the cap 2 overhangs the handle 1 so that when the clippers is laid on the table or other flat surface, it is supported in an 40 inclined position in order to keep the cutter discs from coming in contact with the supporting surface and being damaged thereby. In Figure 1 the dotted line marked 40 indicates the line of support for the clippers when placed on a flat 45 supporting surface.

As will be seen from an inspection of Figure 2 the cutting teeth 7 of the stationary cutter and the cutting teeth 8 of the oscillating cutter are offset so as to have their cutting surfaces 50 and their frictional contact with each other reduced to a minimum. In this way only the teeth of the cutters, which form but a small portion of the cutting disc, are in frictional contact with each other. This is an essential feature in this 55 type of clippers because the power of a solenoid embodied in the handle of the clippers is necessarily limited. Reducing the frictional contact between the cutting teeth in this manner also permits the use of a yielding pressure which is 60 exerted by the spring 18 against the movable cutting blade and have the movable cutting blade oscillate by the limited power generated by the solenoid.

We claim:

- 65 1. Clippers comprising a handle, a fixed supporting rod projecting from one end of said handle, a cutter disc having cutting teeth arranged in a convex curve on the perimeter thereof attached to said supporting rod so as to have its 70 teeth project substantially at right angles to the handle, an axially movable cutter disc having correspondingly arranged cutting teeth on the perimeter thereof surrounding said supporting rod and held yieldingly against said stationary cutter disc, a driving sleeve mounted to oscillate

on said fixed supporting rod and means connecting said driving sleeve with said axially movable cutter disc and means for oscillating said driving sleeve.

2. Clippers comprising a handle having a circular cutting head at one end thereof concentric to the handle, a solenoid axially arranged within said handle, a core mounted to reciprocate within said handle, a driving sleeve concentric to said cutter head and adapted to operate said cutter head and means operated by said reciprocating core to oscillate said driving sleeve.

3. Clippers comprising a hollow handle, a solenoid telescopically mounted within said handle, a base telescopically mounted in said handle on top of said solenoid to hold said solenoid in place in said handle, a substantially vertically arranged oscillating arm mounted to swing in said base, a substantially horizontally arranged rocker arm mounted in said base and engaging said oscillating arm, a core operated by said solenoid to rock said rocker arm and oscillate said swinging arm, a fixed anchoring post mounted on said base and projecting axially from said handle, a circular cutter disc mounted on said anchoring post, a driving sleeve mounted to oscillate on said anchoring post, a cutter disc supported on said driving sleeve to hold it concentric to said fixed cutter disc and means connecting said oscillating arm with said driving sleeve to oscillate said movable cutter disc on the operation of said core by said solenoid.

4. In clippers the combination of a fixed anchoring post, a cutter disc mounted on said anchoring post, a driving sleeve mounted to oscillate on said driving post, a movable cutter disc supported by said driving sleeve concentric to said fixed cutter disc, an oscillating arm mounted to swing in a plane at right angles to the axis of rotation of said driving sleeve, a bearing pin carried by said driving sleeve and adapted to engage said oscillating arm and means for oscillating said oscillating arm to oscillate said driving sleeve and movable cutter disc.

5. In clippers the combination of a fixed anchoring post, a stationary cutter disc mounted on said anchoring post, a driving sleeve mounted to oscillate on said anchoring post, supporting means provided on said driving sleeve, a cutter disc removably mounted on said supporting means, spring means carried by said supporting means to yieldingly hold said removable cutting disc against the underside of said stationary cutting disc, a swinging yoke, an arm carried by said yoke and extending to one side of said driving sleeve substantially parallel thereto, a driving pin carried by said driving sleeve and engaging said arm, a rocker arm engaging said swinging yoke and means for rocking said rocker arm to swing said swinging yoke and arm and oscillate said driving sleeve and movable cutter.

6. In clippers the combination as set forth in claim 5 in which the means for rocking said rocker arm comprises a solenoid, a core operated by said solenoid, an operating member connecting said core with said rocker arm, spring means holding said swinging yoke against one side of said rocker arm and spring means acting on said core to hold said operating member against the other side of said rocker arm, both of the said spring means operating to hold said core in a floating position within said solenoid.

7. In clippers, the combination of a hollow handle having an open end, a solenoid operated core mounted to reciprocate in said handle, a

supporting member located in the open end of
said handle, a cap member for the open end of
said handle adapted to hold said supporting
member in place on said handle, a pivot pin sup-
5 ported on said supporting member, and project-
ing thru said cap member, a driving sleeve
mounted to rotate on said pivot pin, a cutter head

supported on said pivot pin and operated by said
driving sleeve and movement transmitting means
carried by said supporting member operatively
connecting said core with said driving sleeve to
operate said cutter head. 5
